Fig. 4

Fig. 2

FIG. 1 is a front elevational view of a physician's spotlight showing my new design;

FIG. 2 is a rear elevational view thereof;

FIG. 3 is a right side elevational view thereof;

FIG. 4 is a left side elevational view thereof;

FIG. 5 is a top plan view thereof; and

FIG. 6 is a bottom plan view thereof.

The strap is shown in broken lines for illustrative purposes only.

I claim:

The ornamental design for physician's spotlight, substantially as shown and described.
